UNITED STATES PATENT OFFICE

2,120,500

BLADE HOLDER

Gregory Makaroff, Lanesboro, Mass.

Application June 2, 1937, Serial No. 146,076

5 Claims. (Cl. 51—220)

This invention relates to a blade holding or clamping means for use in conjunction with grinding tools and for supporting the blades at the desired position of angular adjustment, and 5 in such position of adjustment as will insure proper contact of the beveled edge of the blade with the grinding disk in a manner to afford an almost perfect sharpening of the blade.

The present invention has reference to certain 10 new and useful improvements in that type of blade holding or clamping means forming the subject matter of Patent No. 2,052,837, granted to me under date of September 1, 1936, and entitled "Grinding device".

15 An object of the invention is to provide a blade holder capable of minutest adjustment and which will be found suitable for supporting the blades in contact either with the side or periphery of the grinding wheel.

20 The invention, together with its objects and advantages, will be best understood from a study of the following description taken in connection with the accompanying drawings, wherein:—

Figure 1 is a side elevational view illustrating 25 the application of the invention when supporting a blade in contact with the periphery of the grinding wheel.

Figure 2 is a similar view illustrating the application of the invention when supporting the 30 blade in contact with the side of the grinding wheel.

Figure 3 is a bottom plan view of the blade holder with certain parts omitted.

Figure 4 is a sectional view taken substantially 35 on the line 4—4 of Figure 3.

Figure 5 is a fragmentary detail sectional view showing clearly the clamping jaws for securing the blade to the holder.

Figure 6 is a detail sectional view taken substantially 40 on the line 6—6 of Figure 4.

Figure 7 is a fragmentary plan view showing in section an adjusting screw and in plan a graduated disk; and

Figure 8 is a plan view of a pivoted block- 45 carrying frame hereinafter more fully referred to.

Referring to the drawings more in detail, it will be seen that in the preferred embodiment thereof the blade holder comprises generally a body member provided with spaced clamps for 50 engagement with the blade to be sharpened for holding the blade in contact either with the periphery of the grinding disk 23 as shown in Figure 1 or with the side of the grinding disk as shown in Figure 2, and the body is equipped with 55 suitable means hereinafter more fully referred to whereby the body of the device may be supported at the desired angle to insure the desired contact with the beveled edge of the blade being sharpened with the periphery or side of the grinding disk 23 as the case may be.

As illustrated the body of the blade clamp and holder consists of a rectangular block of wood or other suitable material and indicated by the reference numeral 5. A pair of strips 24 of metal or other suitable material has the major portions 5 thereof fitting in grooves provided therefor in the underface of the body 5 and extending transversely of the body. The strips 24 are secured to the body through the medium of any number of suitable fastening devices such as screws 25, and at their forward or free ends the strips 24 are rabbeted to form jaws 26.

Cooperating with the jaws 26 are removable jaws 27 which consist of rectangular pieces of metal or the like having down-turned ends 27' 15 overlying the jaws 26 and cooperable therewith for clamping a portion of the blade to be sharpened therebetween. The jaws 27 are illustrated as being removably secured to the strips 24 through the medium of finger screws 28 that 20 thread into suitably aligned openings provided respectively in the strips 24 and jaws 27. To prevent the jaws 27 from rotating relative to the jaws 26 strips 24 on their upper sides are provided with pins 29 that are engaged in notches 30 provided in the rear end edges of the jaws 27. 25

In the bottom or underface thereof the body 5 between the strips 24 is formed with a transverse groove, recess or pocket in which is hinged 30 at one end an adjustment plate 8 that normally fits within the pocket, the latter being indicated by the reference numeral 7.

An adjustment screw 10 threads through the body 5 to engage the plate 8, and obviously, by threading the screw 10 downwardly into engagement with the plate 8 the body 5 and plate 8 may be moved to relative positions of adjustment whereby the body 5 may be adjusted to vary the angular position of the blade during the sharpening thereof without disturbing the set position 40 of the device or blade holder relative to the grinding wheel.

The structure as just described is substantially identical with that forming the subject matter of my aforementioned Patent No. 2,052,837.

In accordance with the present invention there is provided on the side of the body plate 5 a fixed graduated dial 11 while the adjustment screw 10 is provided with a pointer or index 12 adapted to be read against the graduations on the dial 11 whereby a very minute adjustment of the blade holder may be effected to insure the desired proper contact of the blade with the grinding wheel.

Further, in accordance with the present invention there is provided a frame indicated generally by the reference numeral 17. The frame 17 is substantially U-shaped and at the free ends of the sides 18 thereof is pivoted to the body block 5 through the medium of the pivot bolt 9 55 60

which also serves as a pivot for the aforementioned adjustment plate 8. Secured to the cross-bar 19 of the frame 17 is a block 20, the upper side of which is beveled as shown, and this block 5 20 provides a rest for the plate 8 for supporting the plate at an angle to the horizontal. The frame 17 is used, as shown in Figure 2, when it is desired to support the blade 21 to be sharpened in contact with the side of the grinding 10 wheel 23. When it is desired to hold the blade 22 in contact with the periphery of the wheel 23 the frame 17 is swung to the out-of-the-way position, as shown in Figure 1.

As shown, the ends of the blade 22 are clamped 15 between the jaws 26, 27, and in actual practice the initial adjustment of the device is effected by turning the screw 10 to place the body block 5 at the desired position of angular adjustment. A more minute adjustment of the body block 5 20 is had through the medium of the scale plate 13 and the index 15, as is thought to be apparent.

Further, by resort to the frame 17 and block 20 plate 18 may be supported at an angle to the horizontal so that a wider range of adjustment 25 may be had.

Further in accordance with the present invention there is secured to the plate 8 an arcuate graduated bar 13 that rises from the plate 8 and is provided with a slot 14. Secured to the 30 body block 5 is an index member 15 having an edge thereof adapted to be read against the graduations on the scale bar 13, and carried by the index 15 is a screw 16 that is adapted to be threaded home against the bar 13 for securing 35 the body block 5 at the desired angular position of adjustment.

By using the scale bar 13 in conjunction with the dial 11 two or more blades may be sharpened to substantially the same extent so that a unit 40 form sharpening of several blades may be effected with this device.

Having thus described the invention, what is claimed as new is:—

1. A blade holder of the character described 45 comprising a substantially flat body, strips secured to the underside of the body and extending transversely thereof, said strips being provided at one end with jaws projecting beyond an edge of the body, removable jaws cooperable 50 with the first-named jaws, means for securing the removable jaws to the strips in operative position to the first-named jaws for clamping the ends of a blade to be sharpened therebetween, and said body being provided on the underside 55 thereof with a recess, an adjustment plate normally arranged in the recess and hinged at one end to the body, an adjustment screw threaded through the body and engaging the adjustment plate, a circular scale plate on said body concentric to said screw, and an index carried by said screw and adapted to be read against said scale plate.

2. A blade holder of the character described 65 comprising a substantially flat body, strips secured to the underside of the body and extending transversely thereof, said strips being provided at one end with jaws projecting beyond an edge of the body, removable jaws cooperable 70 with the first-named jaws, means for securing the removable jaws to the strips in operative position to the first-named jaws for clamping the ends of a blade to be sharpened therebetween, said body being provided on the underside there-

of with a recess, an adjustment plate normally arranged in the recess and hinged at one end to the body, an adjustment screw threaded through the body and engaging the adjustment plate, a circular scale plate on said body concentric to 5 said screw, an index carried by said screw and adapted to be read against said scale plate, an arcuate scale plate extending upwardly from said adjustment plate, and said body plate being provided with a slot to accommodate said 10 arcuate scale plate, an index on said body adapted to be read against the graduations on the arcuate scale plate, and interengaging means on said index and said arcuate scale plate for securing said body block at the desired position 15 of adjustment.

3. A blade holder of the character described comprising a substantially flat body, strips secured to the underside of the body and extending transversely thereof, said strips being provided at one end with jaws projecting beyond an edge of the body, removable jaws cooperable with the first-named jaws for securing the ends of a blade therebetween, said body being provided on the underside thereof with a recess, an adjustment 20 plate normally arranged within the recess and hinged at one end to the body, an arcuate graduated scale plate extending upwardly from said adjustment plate and through a slot in said body, and an index mounted on said body and adapted 25 to be read against the graduations on said scale plate in effecting an angular adjustment of the body relative to said adjustment plate.

4. A blade holder of the character described comprising a substantially flat body, strips secured to the underside of the body and extending transversely thereof, said strips being provided at one end with jaws projecting beyond an edge of the body, removable jaws cooperable with the first-named jaws for securing the ends 40 of a blade therebetween, said body being provided on the underside thereof with a recess, an adjustment plate normally arranged within the recess and hinged at one end to the body, an arcuate graduated scale plate extending upwardly from said adjustment plate and through a slot in said body, and an index mounted on said body and adapted 45 to be read against the graduations on said scale plate in effecting an angular adjustment of the body relative to said adjustment plate, said scale plate being provided with an arcuate slot, and a screw carried by said index and working in said slot and adapted to be threaded home into binding engagement with said scale plate for securing the body at the desired 50 angle of inclination.

5. A blade holder of the character described comprising a substantially flat body, jaw members provided at one edge of said body for supporting a blade to be sharpened in substantially spaced parallel relation with one edge of said body, an adjustment plate hinged at one end thereof to the underside of said body, a substantially U-shaped frame including side members pivoted at one end thereof to said body at opposite ends of said body and a cross member connecting the free ends of said side members, and a "rest" for said adjustment plate carried by said cross member and having a beveled upper surface upon which said adjustment plate is adapted to seat, as and for the purpose specified.

GREGORY MAKAROFF.
